UNITED STATES PATENT OFFICE

1,988,544 APPARATUS FOR TESTING YARNS OR THE LIKE

Heinrich Dietz, Harleshausen, near Cassel, Germany

Application March 28, 1931, Serial No. 526,103

In Germany June 10, 1930

8 Claims.

(Cl. 73—51)

My invention relates to improvements in apparatus for testing yarns or the like, and more particularly in apparatus for testing the tensile strength of yarns or the like, which apparatus consist of means for continuously feeding the yarn and forming the same into a loop carrying a weighted body adapted to tear the yarn when a portion of reduced strength is passed through the apparatus. In apparatus of this type the loop is formed between a pair of feed rollers both connected with a driving mechanism. If in such apparatus the feed rollers are rotated at uniform circumferential velocity the loop is gradually enlarged by the stretching of the thread so that the weighted body is gradually lowered, and for compensating such extension of the loop it has been proposed to drive the leading feed roller at increased circumferential velocity. In one construction a conical feed roller is used which is adapted to be shifted in axial direction for placing the yarn on portions of different diameter and thus increasing the circumferential velocity. In an apparatus heretofore constructed by me hand-operated means are provided for shifting the conical feed roller. The object of the improvements is to provide an apparatus of this type in which the conical feed roller is automatically shifted in axial direction for varying the velocity of the leading end of the thread so that the weighted body is maintained at constant level, and with this object in view my invention consists in providing mechanism controlled by the weighted body for shifting the conical roller, the said mechanism being adapted to be thrown into operation by the weighted body leaving its normal position and to be thrown out of operation either automatically or at the beginning of the return movement of the weighted body or when the weighted body has been restored to normal position.

For the purpose of explaining the invention an example embodying the same has been shown in the accompanying drawings in which the same reference characters have been used in all the views to indicate corresponding parts. In said drawings

Fig. 1 is an elevation showing the apparatus, Fig. 2 is a top plan view thereof with some parts removed.

Fig. 3 is a sectional elevation on line 3—3 of Fig. 2 showing the coupling device for the operating mechanism.

Fig. 4 is a sectional elevation taken on the line 4—4 of Fig. 3.

Figs. 5 and 6 are respectively a plan view and an elevation showing a part of the coupling member for connecting the mechanism for shifting the conical drum with its driving shaft.

Fig. 7 is a top plan view with parts omitted, and Fig. 8 is a detail of yarn controlling means shown in Fig. 1.

In the example shown in the figures the apparatus comprises two pillars 50 rising from a base plate 51 and formed with brackets 52 and 53. On the top part of the pillars a shaft 33 is mounted which is axially shiftable, and on the said shaft a drum is loosely mounted between two collars 73, 74. The drum comprises a conical section 34, a cylindrical section 54 and a pulley 55, the said drum being adapted to be rotated from a suitable source of power by means of a belt 56. The cylindrical section 54 is in engagement with a roller or friction gear 57 which is yieldingly pressed against the section 54 and the roller or pulley 57 is yieldingly held against a roller or pulley 80. This roller 80 is mounted on a shaft 81, carrying a reel 58, so that the rotary movement is transferred to the said reel from the cylindrical section 54. The conical section 34 is in engagement with a roller 59. Below the said roller a pulley 2 is rotatably mounted on a bracket 61 fixed to a lever 3, rockingly mounted at 62 and having a weighted body 4 longitudinally adjustable thereon. On the base plate 51 a plate 60 is mounted which provides a support for mechanism for controlling the supply of the yarn 1 to be tested to the drum 34, 54.

Fig. 8 shows in detail the yarn controlling means, wherein the yarn to be tested is shown as passing between a row of pins a^1 fixed on plate 60 and another row a^2 on a rod a^3 after the manner of the well-known tortuous course tension devices. Rod a^3 is supported for reciprocation by a pin a^1 and is connected through a lever a^4 to one arm of a three-armed scale beam a^5 ; provided at one end with a weight a^6 and at the other with a roller a^7 . A guide roller a^8 is fixed to plate 60 and an adjusting screw a^9 on said plate serves to adjust the lower end of lever a^4 and so to determine the position of the movable pins a^2 . The thread coming from a cop or other source of supply is led between the two sets of pins, over roll a^1 , under roll a^3 , and thence to drum 54, whereby the thread is given a certain tension which is maintained throughout. The desired tension is determined by the adjustable weight a^6 .

In the operation of the machine, i. e., while the drum 54 is driven by belt 56 the screw a^9 is adjusted to move the rod a^3 , the pins a^2 thereon, and the lever a^4 to such an extent as to tension the thread sufficiently to bring the straight arm of the scale beam into horizontal position. If now the tension of the yarn increases the roll a^7 will be drawn lower, thereby moving lever a^4 clockwise and so moving pins a^2 in the direction of the arrow, thus reducing the tension on the thread. If the thread tension decreases, the roller a^7 rises and lever a^4 moves counterclockwise, forcing rod a^3 and pins a^2 to the left so as to increase the friction of the thread on the pins a^1, a^2 and so to increase the tension. In this way alterations of tension on the thread coming from the source of supply are compensated so that it is always under uniform tension as it leaves the controlling means. This is also true of a counter shown at the top of posts 50 which counts the rotations of drum 54 and so measures the length of the yarn being tested.

In the operation of the apparatus the yarn to be tested is passed through the controlling mechanism mounted on the plate 60 and upwardly therefrom to the cylindrical portion 54 of the drum where it is compressed between the said portion and the roller 57, so that a regular amount of yarn is continuously passed through the testing apparatus. From the cylindrical section 54 the yarn is passed downwardly and trained about the pulley 2 whereupon it is passed upwardly again over the roller 59 and the conical section 34, the roller 59 pressing the yarn against the said conical section. The yarn leaving the section 34 is wound on the reel 58. The axle 75 of friction gear 57 is mounted in a bearing 76, which bearing is slidably mounted in a slot 77 of an arm 78 on the standard 50. A spring 79' presses against the slide 76 whereby the friction gear 57 is yieldingly pressed against the drum 54. Another roller or friction gear 80 bears against friction gear 57, the axle 81 of roller 80 being journaled in a second slide 76'. The friction gear 80 is pressed against friction gear 57 by means of a spring 79' bearing against the slide 76'. The axle 81 at its outer end carries a reel 58 and it will be evident that the rotation of the reel is caused by the drum 54 which is driven by belt 56, the rotation of the drum 54 being transmitted to the reel through friction gears 57 and 80 and the shaft 81. The axle 59' is journaled in a slide 59' mounted in a slot 96' of an arm 96 of the front standard 50. A spring 79' bearing against the slide 59' presses the roller 59 against the drum 34. Normally the yarn will pass through the testing apparatus in a regular way. But if a weak portion of the yarn passes through the apparatus it is broken by the tension imparted thereto by the weighted pulley 2. By the tension imparted to the yarn by the weighted pulley 2, the said yarn is stretched, so that the pulley 2 tends to move downwardly and therefore means have been provided for compensating the said stretching, and such means consist in mechanism for shifting the drum 34, 54 in an axial direction so that the yarn is passed over portions of varying diameter of the conical section 34, and the length of yarn fed by the said conical section is varied as compared to the constant feed of yarn by the cylindrical section 54. In a construction now in use the shaft 33 screws in a screw-threaded bore of one of the pillars 50 and it is adapted to be turned by hand for shifting the conical section 34. The shaft 33 is supported by two upright standards 50 on the bed plate 51, the

rear standard 50 being provided with a screw-threaded opening 50' and the shaft 33 being provided with a correspondingly threaded portion 33'. When the shaft is turned by means of the pulley 72 which is keyed to shaft 33, it will move axially in one direction or the other according to the direction of rotation of the pulley by reason of the coaction of said screw threads. In my improved apparatus automatic means are provided for turning the shaft 33, which means will now be described.

The shaft 33 is connected by a belt gearing 32 with a shaft 23 mounted in suitable brackets 64 and 65 rising from the base plate 51. The rotation of shaft 23 is transmitted to shaft 33 by means of belt gearing comprising pulleys 82 and 72 fixed to the respective shafts and connected by a belt 32. On the said shaft gear wheels 24 and 26 are rotatable the hubs 27 and 28 of which are formed with coupling jaws adapted for engagement with a coupling member 29 shiftable and non-rotatable on the shaft 23, the said coupling member being engaged by an arm 30 acted upon by an electro-magnet 13 and a spring 31 tending to shift the coupling member 29 in opposite directions and into engagement either with the hub 27 or with the hub 28. The gear wheel 24 is in engagement with a gear wheel 20 secured to a shaft 22 mounted in the bracket 65 and a bracket 66. The gear wheel 26 is in mesh with an intermediate gear wheel 25 mounted in the brackets 65 and 66 and meshing with a gear wheel 21 secured to the shaft 22. Thus, when rotating the said shaft 22 the gear wheels 24 and 26 are rotated in opposite directions. The shaft 22 is adapted to be coupled with a shaft 19 continuously rotated from an electromotor 36 through the intermediary of pulleys 67 and 37 and a belt 18. The clutch connecting the shafts 19 and 22 comprises a disk 17 keyed to the shaft 22 and a disk 38 keyed to the shaft 19, and it is controlled by an electromagnet 12 the armature 14 of which is adapted to rock a bell crank lever 15 into and out of engagement with the clutch 17, 38. Armature 14 is connected by pin and slot connection 84, 85 to a bell-crank lever 15 and the armature is normally drawn downwardly by a spring 83, the lever being moved in one direction when the electro-magnet is energized and in the contrary direction when the electro-magnet is deenergized, the first movement connecting the one-rotation coupling 17, 38 whereas the other places the bent end of the bell-crank lever in position or engagement with the finger 70 for unclutching the coupling. As is shown in Figs. 3 and 4 the disk 38 is formed with a flange 68 embracing a reduced portion 69 of the disk 17, and the said flange is formed with notches 38'. In a bore of the disk 17 a cylindrical key 16 is rockingly mounted which extends with a semi-cylindrical end 16' into a corresponding recess of the portion 69 of the disk 17 and into position for engagement with the notches 38'. To the key 16 a block 70 is secured which is in position for engagement with the bell crank lever 15, and which is acted upon by a spring 71 tending to rock the same with its cylindrical portion 16' into locking engagement with the recesses 38'. The electromagnet 12 is included in a circuit comprising a source of electric energy and two mercury contacts 10. A pair of mercury contacts 11 are included in an electric circuit comprising the said source of electric energy and both electromagnets 12 and 13. The mercury contacts 10 and 11 are located at opposite sides of one of the pillars 50 on down-

ward extensions 52' and 53' of brackets 52 and 53 respectively, and they cooperate each with a contact making bridge 9 mounted on a lever 8 rockingly suspended from the brackets 52 and 53 respectively.

The levers 8 are made integral with downwardly directed arms 7 carrying inwardly and downwardly inclined abutments 6 located in the paths of pins 5 secured to the opposite ends of the lever 3. If therefore the lever 3 is rocked with one of its ends downwardly the corresponding pin 5 engages one of the abutments 6 located one above the other, thus rocking the corresponding lever 8 into position for closing the mercury contacts 10 or 11.

Contacts 86, 87 are provided on the bed plate of the machine for connection to a source of current. A conductor 88 leads from the contact 86 to the right-hand well of the mercury switch 10 and the conductor 89 leads from the left-hand well of the switch to electro-magnet 12. A return conductor 90 returns from magnet 12 to original contact 87.

The conductor 88 is connected to the right-hand well of switch 11 by means of a branch 91. From the left well of this switch a conductor 92 leads to the electro-magnet 13 whose winding is connected to the conductor 89 by means of a conductor 93. The circuit formed on closing the mercury switch 10 upon lowering the pulley 2 to a sufficient degree is as follows:

Contact 86, a conductor 88, right-hand well of mercury switch 10, bridge 9, left-hand well of switch 10, conductor 89, winding of electro-magnet 12, conductor 90, contact 87.

Upon closing the circuit through switch 11 due to the undue elevation of pulley 2 the following circuit is closed:

Contact 86, conductor 88, conductor 91, right-hand well of switch 11, bridge 9, left-hand well of switch 11, conductor 92, winding of electro-magnet 13, conductors 93 and 89, winding of electro-magnet 12, conductor 90, contact 87.

If the switch 10 is closed, the magnet 12 will be energized whereupon the clutch of Figs. 3 and 4 will be engaged. The reversible coupling 29 remains in the position shown in Fig. 2 in which the teeth of reversible clutch member 29 engage the teeth of hub 28 on gear 26. If however the switch 11 is closed then in addition to the magnet 12, the magnet 13 is also energized so that in addition to the closing of the clutch of Figs. 3 and 4 the reversible clutch member 29 is moved so as to bring its teeth into engagement with the teeth of hub 27 of gear 23 whereby the direction of rotation of shaft 23 is reversed.

In the operation of the apparatus the yarn to be tested is continuously supplied through the apparatus 60, thence over the cylindrical portion 54 of the drum, the pulley 2, the roller 59, the conical portion 34 of the drum and the reel 58, and it is pressed into frictional engagement with the cylindrical portion 54 and the conical portion 59 by the rollers 57 and 59. The drum is rotated by means of the belt gearing 56, and such rotary movement is transmitted by the roller 57 to the reel 58. The yarn passing through the apparatus is put under tension by the pulley 2, the said tension being adapted to be regulated by shifting the weight 4 on the lever 3 outwardly or inwardly, and if a weak portion of the yarn passes through the apparatus it is broken by the weight of the pulley 2. The number of the breaks occurring in a certain length of yarn indicates the quality of the material.

Since the yarn is not uniform in structure but rather has thick places and thin places of substantial length (that is, its number varies) the stretching of the yarn through the action of the weight 4 is not uniform. In case the yarn should run unusually fine for a considerable length it will stretch beyond the normal and so the pulley 2 will sink; if the yarn is unusually thick and strong for a considerable length then the stretch is less and the pulley will rise. For regulating the feeding movement of the members 34 and 59 so that the pulley 2 remains substantially at the same height, the drum 34, 54 is adapted to be shifted in an axial direction, so that parts of different diameter engage the yarn trained over the conical portion 34. For example, if the yarn 1 is stretched so far that the pulley 2 moves downwardly, the lever 3 is rocked so as to bring pin 5 into engagement with the abutment 6. Thereby the lever 8 is rocked, and the circuit including the mercury contacts 10 is closed by the bridge 9.

By closing the said circuit the electromagnet 12 is energized, and the bell crank lever 15 is rocked into position for releasing the block 70 which therefore is rocked by the spring 71 into the position in which the key 16 couples the disks 17 and 38. Thereupon the shaft 19 imparts rotary movement to the shaft 22 and the gear wheels 20 and 21 carried thereby which rotary movement is transmitted to the gear wheels 24 and 26 rotating in opposite directions. The electromagnet 13 is not energized and therefore the coupling member 29 remains in engagement with the hub 28 of gear wheel 26, and rotary movement is transmitted by the said coupling member to the shaft 23, the gearing 32 and the shaft 33, the said shaft being rotated in a direction for shifting the drum 34, 54 in a direction for placing the yarn 1 on a portion of the conical part 34 of increased diameter, so that the said conical part feeds the yarn at increased velocity.

When the pulley has been elevated, and the pin 5 has released the abutment 6, the lever 8 returns to normal position in which the circuit of the electromagnet 12 is broken at the terminals 10.

Now the bell crank lever 15 returns into initial position and it is engaged by the block 70 after a complete rotation of the disk 38, so that the block 70 is rocked against the tension of the spring 71 into position for disconnecting the disks 17 and 38.

If the pulley 2 is lifted by the loop of the yarn 1 above the normal position due to a heavier and stronger length of yarn which stretches less than the preceding length of yarn, the left hand pin 5 engages the cooperating abutment 6 and it rocks the lever 8 with its bridge 9 downwardly and into position for closing the contacts 11.

The circuit of said contacts includes both electromagnets 12 and 13 and therefore the gear wheels 24 and 26 are rotated from the electromotor 36 in the manner described above. However by reason of the energization of the electromagnet 13 the coupling member 29 is caused to engage the hub 27 of the gear wheel 24, so that the shaft 23, the gearing 32 and the shaft 33 are operated in a direction opposite to that described above and the conical portion 34 of the drum moves into a position for engaging the yarn 1 with a part of reduced diameter, therefore the feed of the yarn by the said conical portion is reduced as compared to the feed by the cylindrical portion 54 and the pulley sinks into normal position.

The electromagnet 13 acts only as long as the pin 5 of the left hand arm of the lever 3 engages

the abutment 6, and when the lever 8 is returned to its normal position the electromagnet 13 is de-energized and the coupling member 29 is disengaged from the hub 27 of gear wheel 24.

When the pulley 2 is lowered by the loop of the yarn 1 below the normal position due to a lighter and weaker length of yarn which stretches more than the preceding length of yarn, the right hand pin 5 engages the cooperating abutment 6 and it rocks the lever 8 with its bridge 9 upwardly and into position for closing the contacts 10.

The circuit of said contacts includes both electromagnets 12 and 13 and therefore the gear wheels 24 and 26 are rotated from the electromotor 36 in the manner described above. However by reason of the energization of the electromagnet 13 the coupling member 29 is caused to engage the hub 27 of the gear wheel 24, so that the shaft 23, the gearing 32 and the shaft 33 are operated in a direction opposite to that described above and the conical portion 34 of the drum moves into a position for engaging the yarn 1 with a part of reduced diameter, therefore the feed of the yarn by the said conical portion is reduced as compared to the feed by the cylindrical portion 54 and the pulley sinks into normal position.

The electromagnet 13 acts only as long as the pin 5 of the right hand arm of the lever 3 engages the abutment 6, and when the lever 8 is returned to its normal position the electromagnet 13 is de-energized and the coupling member 29 is disengaged from the hub 27 of gear wheel 24.

When the pulley 2 is lowered by the loop of the yarn 1 below the normal position due to a lighter and weaker length of yarn which stretches more than the preceding length of yarn, the right hand pin 5 engages the cooperating abutment 6 and it rocks the lever 8 with its bridge 9 upwardly and into position for closing the contacts 10.

The circuit of said contacts includes both electromagnets 12 and 13 and therefore the gear wheels 24 and 26 are rotated from the electromotor 36 in the manner described above. However by reason of the energization of the electromagnet 13 the coupling member 29 is caused to engage the hub 27 of the gear wheel 24, so that the shaft 23, the gearing 32 and the shaft 33 are operated in a direction opposite to that described above and the conical portion 34 of the drum moves into a position for engaging the yarn 1 with a part of reduced diameter, therefore the feed of the yarn by the said conical portion is reduced as compared to the feed by the cylindrical portion 54 and the pulley sinks into normal position.

The electromagnet 13 acts only as long as the pin 5 of the right hand arm of the lever 3 engages the abutment 6, and when the lever 8 is returned to its normal position the electromagnet 13 is de-energized and the coupling member 29 is disengaged from the hub 27 of gear wheel 24.

When the pulley 2 is lowered by the loop of the yarn 1 below the normal position due to a lighter and weaker length of yarn which stretches more than the preceding length of yarn, the right hand pin 5 engages the cooperating abutment 6 and it rocks the lever 8 with its bridge 9 upwardly and into position for closing the contacts 10.

The circuit of said contacts includes both electromagnets 12 and 13 and therefore the gear wheels 24 and 26 are rotated from the electromotor 36 in the manner described above. However by reason of the energization of the electromagnet 13 the coupling member 29 is caused to engage the hub 27 of the gear wheel 24, so that the shaft 23, the gearing 32 and the shaft 33 are operated in a direction opposite to that described above and the conical portion 34 of the drum moves into a position for engaging the yarn 1 with a part of reduced diameter, therefore the feed of the yarn by the said conical portion is reduced as compared to the feed by the cylindrical portion 54 and the pulley sinks into normal position.

The electromagnet 13 acts only as long as the pin 5 of the right hand arm of the lever 3 engages the abutment 6, and when the lever 8 is returned to its normal position the electromagnet 13 is de-energized and the coupling member 29 is disengaged from the hub 27 of gear wheel 24.

The electromagnet 13 acts only as long as the pin 5 of the right hand arm of the lever 3 engages the abutment 6, and when the lever 8 is returned to its normal position the electromagnet 13 is de-energized and the coupling member 29 is disengaged from the hub 27 of gear wheel 24.

the abutment 6, and therefore means are provided for holding the coupling member 29 in coupling engagement with the hub 27 until the shaft 23 has performed a complete revolution. 5 Such mechanism is necessary because otherwise the spring 31 would prematurely retract the coupling member 29 from the hub 27. As is shown in Figs. 5 and 6 the flange of the coupling member 29 located at the side of the gear wheel 24 10 is formed with a notch 40 which is normally in register with a pin 35 secured to the plate 66. If the electromagnet shifts the coupling member 29 into engagement with the hub 27, and rotary movement of the coupling member 29 is started, 15 the pin 35 engages at the rear of the flange of the coupling member, so that it prevents the said coupling member from being retracted by the recess 40 before the coupling member has performed a complete rotation.

The shafts 33 and 23 should rotate as long as the lever 3 is more than a minimum distance from horizontal position, it being remembered that the total oscillation of lever 3 is only through a small arc. The lever when at rest should be in substantially horizontal position, wherein the circuits through mercury cups 10 and 11 are broken. Preferably the drive is stopped as soon as possible after the lever has started back toward horizontal position (i. e., as soon as the circuit is broken which was closed by the movement of lever 3 due to undue tension or slackness of the yarn) but it is not desirable to continue the drive until the lever is horizontal, as this would continue the rotation of shaft 33 too long and so would over-compensate for the previous tension or slackness of the yarn. The parts are therefore so proportioned that either lever 7 will break the circuit through its mercury cups shortly after the lever 3 starts its return toward normal, but the lever 3 will be moved very nearly to normal horizontal position by reason of the fact that shafts 22 and 23 must each continue to rotate until the end of a full rotation, shaft 23 40 rotating until notch 40 is opposite pin 35 and shaft 22 rotating until block 70 strikes lever 15. Notch 40 and clutch member 70 bear a fixed relation to one another since gears 20 and 24, as well as 21 and 26, have respectively the same 45 number of teeth, so that a rotation of one shaft requires a rotation of the other. Shaft 22 is stopped after one rotation by reason of its single-rotation clutch, and so shaft 23 is also stopped in such a position as to bring notch 40 opposite pin 35. After the clutch member 29 is released by pin 35, it can only be set in rotation again by operation of lever 15 to release clutch member 70 and permit the one-revolution clutch 38-17 to be clutched in. Shafts 23 and 22 are held against relative rotation by gears 26, 25 and 21, as gears 26 and 21 have the same number of teeth and as the clutch 38-17 can only be unclutched after a complete rotation the shaft 23 can only stop after a full rotation. Therefore shaft 23 can only stop in a position where notch 40 is opposite pin 35, and so clutch member 29 can be engaged with clutch member 27 again by the operation of electromagnet 13.

I claim:

70 1. An apparatus for testing yarn or the like, comprising means for continuously feeding the yarn to be tested, said means including a device for uniformly feeding the yarn and a shiftable conical roller about which the yarn is trained for feeding the yarn, a weighted body bearing on a

loop of yarn located between said device and conical roller, and automatic means controlled by said weighted body for shifting said conical roller and the yarn engaged thereby relatively to each other.

2. An apparatus for testing yarn or the like, comprising means for continuously feeding the yarn to be tested, said means including a cylindrical roller and a conical roller about which the yarn is trained, a weighted body bearing on the portion of said yarn located between said rollers, and automatic means controlled by said weighted body for shifting said yarn and conical roller relatively to each other axially of said conical roller.

3. An apparatus for testing yarn or the like, comprising means for continuously feeding the yarn to be tested, said means including a cylindrical roller and a conical roller about which the yarn is trained, a screw-threaded shaft carrying said conical roller, a relatively fixed part in which said shaft screws, a weighted body bearing on the part of said yarn located between said rollers, and automatic means controlled by said weighted body for turning said shaft.

4. An apparatus for testing yarns or the like, comprising a device for uniformly feeding the yarn and a conical roller for variably feeding the yarn, a screw-threaded spindle on which said conical roller is loosely mounted, a relatively fixed part in screwing engagement with said screw-threaded spindle, a weighted body bearing on the part of the yarn located between said device and the conical roller, and automatic means controlled by said weighted body for turning said screw-threaded spindle, said automatic means comprising a continuously rotating driving member, a driven member, coupling means intermediate said driving and driven members for transmitting one or more complete rotations to said driven member, including oppositely rotating gears for said driven member, for turning it respectively in opposite directions, and means for coupling either one of said gears to said driven member and to said screw-threaded spindle to rotate said spindle.

5. An apparatus for testing yarn or the like, comprising means adapted to engage the yarn at spaced parts of its length and to feed the same, a weighted body adapted to engage the yarn at the portion located between said parts for putting the same under constant tension, automatic means controlled by said weighted body for varying the relative feed of the yarn at the said parts, said automatic means comprising a driving member, a driven member, electrical means for connecting said driving and driven members, said means including a circuit, a switch included in the circuit of the said electrical means and comprising a rockable switch lever, inclined abutments on said switch lever, and a lever carrying said weighted body and adapted to engage said inclined abutment for rocking said switch lever.

6. In a yarn testing machine, a constant feed for a yarn, a variable feed for said yarn including a tapered pulley and means for pressing the yarn against its surface, means between said two feeding means for exerting constant tension on the yarn, and means controlled by the movement of said tensioning means when it causes slack in the yarn for changing the point of contact of said yarn with said tapered pulley axially of the pulley to vary the rate of feed of the yarn.

7. In a yarn testing machine, a constant feed for a yarn, a variable feed for said yarn including a tapered pulley and means for pressing the yarn

against its surface, means between said two feeding means for exerting constant tension on the yarn, a constantly driven member, disengageable connections from said constantly driven member for moving the pulley either to carry the yarn toward its smaller end or toward its larger end, and means controlled by movement of said tensioning means when it causes slack in the yarn for determining the time of engagement of said connections and the direction in which the pulley is moved thereby.

5. In a yarn testing machine, a constant feed for a yarn, a variable feed for said yarn including a shiftable tapered pulley and means for press-

ing the yarn against the periphery of the pulley, means between said two feeding means for exerting a constant tension on the yarn including a floating element bearing on the yarn, a pair of oppositely movable devices, means alternatively connectable with said devices for moving said pulley axially and relatively to the yarn, and means controlled by the position of said floating element for determining the time or order of engagement of said moving means with said devices and thereby the direction in which said pulley is moved thereby.

10

HEINRICH DIETZ.
